UNITED STATES PATENT OFFICE.

LEONARD CHAPMAN, OF LONDON, ENGLAND.

IMPERMEATING INSTRUMENT.

1,324,955.

Specification of Letters Patent. Patented Dec. 16, 1919.

Application filed September 13, 1918. Serial No. 253,999.

To all whom it may concern:

Be it known that I, LEONARD CHAPMAN, a subject of the King of England, residing at London, England, have invented certain 5 new and useful Improvements in Impermeating Instruments, of which the following is a specification.

The object of this invention is to provide means for introducing particles of solids 10 (such as powdered graphite or mica or finely-divided material) into the steam supply of engines or into the steam-spaces of boilers and also for the ready securing of the said means on the cylindric exterior of 15 horizontal or vertical or inclined pipes of various diameters or to objects having flat surfaces.

In the apparatus hereinafter described the method employed for gradually removing 20 the finely-divided material from a container thereof which it occupies in the form of a column, is the gradual washing away of the material at the foot of the column around the outer margin thereof by water 25 of condensation which carries it into the steam-supply.

An impermeating-instrument according to this invention comprises at the top, a tube of circular exterior which is to contain a 30 column of finely-divided material and has a sight-feed chamber beneath it and communicating with it, and below the sight-feed chamber a junction-pipe combined with an inclined bracket.

35 An impermeating-instrument according to this invention is illustrated in the accompanying drawings, in which—

Figure 1 is a vertical central section of the impermeating-instrument;

40 Figs. 1^a and 2^a are sections, on the lines 1^a and 2^a respectively, in Fig. 1, of a detail of that figure hereinafter referred to;

Fig. 2 is an elevation of the instrument corresponding to Fig. 1, except that the 45 bracket forming the bottom of the instrument is rotated out of the position it occupies in Fig. 1 through 180 degrees as hereinafter described.

Fig. 3 is, as to its upper part, a vertical 50 central section of the instrument shown in Figs. 1 and 2, and as to its lower part, a partial elevation of the instrument with the bracket aforesaid in a position corresponding with that in which it is shown in Fig. 2; 55 Fig. 4 is a sectional plan on the line 4—4 in Fig. 3;

Fig. 5 is a plan of the upper part of Fig. 1 in section on the line 5—5 in Fig. 1;

Fig. 6 is a plan of Fig. 2; and

Fig. 7 is a view of part of Fig. 3 modified to show an alternative construction with eight bolts hereinafter referred to.

Like letters represent like parts throughout the drawings.

In these drawings, an endwise-adjustable 65 tube T of circular exterior, which is to contain the column of finely-divided material has near its lower end perforations P, and also, at a lower level, notches N. These perforations and notches enable said lower 70 end to serve as a duplex valve V. Screw-threads ST¹ are provided on the upper exterior circumference of the tube. A jacket J provided with heat-radiating wings W encircles said tube and is clear thereof intermediate of the ends of said tube, to afford an annular space AS between the jacket and the tube. On the upper interior of the jacket are screw-threads JT which engage the threads ST¹ on the tube. An annular 75 valve-face F is formed on the lower part of the jacket-interior in proximity to and co-operating with the exterior of the aforesaid valve V near the level of the perforations P therein, the lower edges of which are, in 80 the drawing, on the level of the shoulder F¹ of the valve-face F.

A conical disk D is held stationary in a funnel FL hereinafter again referred to and forming the lower portion of the jacket-casting; the disk is co-axial with the lower end of the inner tube T, and has its nose DN directed upwardly thereinto. The outer margin DM of said disk is shaped to form an annular valve-face in proximity to and co-operating with the interior of the aforesaid valve V at the level of the notches N 95 therein. The stem D¹ of the disk D extends downwardly therefrom as shown, into a sight-feed chamber SF beneath the jacket J, and integral with the funnel FL, which latter forms a downward continuation of the walls of the jacket J.

The disk D and stem D¹ have a central bore D² extending through them and the 105 disk and bore are blocked at the upper end of the bore by a screw D³ screwed into a threaded portion of the upper end of said bore. Integral with the upper portion of the stem D¹ which has a downwardly-depending conical portion D⁴, are four radial 110 wings D⁴ which support the coned disk D

- centrally in the funnel FL, and are cut away by the central bore D² so that openings D⁵ from the funnel FL into the bore exist at the bottom of the funnel between the wings D⁴.
- 5 The lower portion of the stem is formed at D⁶ as a circular plug which fits tightly into and closes the funnel-exit, except for the openings D⁵ into the central bore D² aforesaid, the said circular plug being integral 10 with the wings D⁴ and having below it a reduced portion or nozzle D⁷ through which the bore delivers into the upper part of the sight-feed chamber. This nozzle is centralized in the upper opening SF¹ of the sight-15 feed device SF by four small radial wings D⁸ on the nozzle between which there is free passage upward from the sight-feed chamber SF around the nozzle D⁷ as far as the underside of the plug D⁶.
- 20 The sight-feed chamber SF is in the form of a short horizontal cylinder and in the ends of the cylinder are transparent windows SF², SF³, secured in the usual manner and in themselves not novel.
- 25 Studs S which project from the inside of the inner tube near the top thereof as shown, are provided in order that a rotating tool of a suitable kind can be engaged with them to adjust the tube T endwise by screwing it 30 up or down in the screw-threads JT of the jacket.

A cap-seat is formed on the jacket as an upstanding flange JT² a little above the level of the top end of the inner tube T and concentric therewith but larger, so that an annular gutter G exists between the outside of said tube and the inside of said flange.

A cap K closes fluid-tight the upper end of the instrument, being seated like a valve 40 upon the beveled face or cap-seat JT² of the flange JT². This cap has a beveled rim K¹ which bears upon the cap-seat and extends therefrom downwardly and inwardly. The cap also has in its underside a central cavity 45 K² sloping downwardly and outwardly from the center thereof and meeting the said beveled rim so as to form where they meet a drip-angle ring K⁴ directed downwardly toward the aforesaid annular gutter G. Any 50 products of condensation forming on the underside of the cap K will run down to the drip-angle ring and drop therefrom into the gutter G.

A bridge-piece BP straddles the upper 55 end of the jacket when the parts are in the positions in which they are shown in Figs. 1, 2 and 5. A screw-threaded spindle SP bears at its lower end upon a disk K⁵ in a recess K⁶ in the top of the cap K and is encircled 60 by a collar s pinned to it by a pin s¹ and provided with flanges s² which are engaged by a cover-plate K⁷ held in place by screws K⁸ in the cap, the said flanges s² being circular so that the spindle SP can be rotated 65 in the cap but cannot be drawn out of it

upwardly. At the upper end of the spindle SP is a hollow handle SH and on the spindle are screw-threads S² which engage a threaded bore in the central boss b of the bridge-piece BP. By rotating the spindle 70 SP the cap K can be screwed down upon or raised clear of the flange JT².

Flanges BF¹ and BF² (the former constituted by a ring carried on and forming the base or lower part of the bridge-piece) 75 respectively extend horizontally therefrom, the flange BF² being down-turned and extending inwardly, as shown. Corresponding flanges JF¹ and JF² with which the flanges BF¹ and BF² respectively engage are provided on the outside of the jacket J, the flange JF¹ being directed horizontally and inwardly and the flange JF² horizontally and outwardly. The flanges BF¹ and JF² 80 are completely circular; the flanges BF² and JF¹ are sectors only.

The bridge-piece and the cap K secured to it as aforesaid by the spindle SP are together pivoted to the jacket by a pivot PV fixed in a lug J³ on the jacket and passing 90 through a lug B² formed on the ring BF¹; the axis of this pivot is vertical, so that if the cap K be first raised clear of the jacket by operation of the spindle SP the cap and bridge-piece can thereafter be swung clear 95 from the position in which they are shown in Figs. 1, 2, 3 and 5 into the position in which they are shown in Fig. 6, thus leaving the inner tube I open for inspection, cleansing or recharging.

Cast upon one wall of the jacket and sight-feed chamber SF (the wall which is to the right hand in Figs. 1, 5 and 6) are steam-conduits SC¹, SC³ (Fig. 1) connected by an intermediate annular steam-conduits SC², 105 the latter covered at its outer side by an inspection-cap IC held in place by a central screw IC¹. The lowest conduit SC¹ leads upward from the annular passage-way which below the collar D⁶ is left around the 110 lowest portion of the stem D¹ in the opening SF¹ in the sight-feed chamber, to the annular conduit SC², whence the conduit SC³ proceeds to the upper end of the annular space AS surrounding, as hereinbefore explained, 115 the inner tube T. From the upper end of this annular space AS a helical groove HG extends across the face of the threads in the bore of the jacket J, upwardly into the gutter G for the purpose of draining that gutter 120 into the annular space AS.

The funnel FL hereinbefore referred to, is in fluid-tight connection at its upper end with the bottom of the inner tube T, which latter makes a sliding fit with it.

At the bottom of the sight-feed chamber is a flange SF⁴ with a central opening SF⁵ through it leading downward from the bottom of the interior of the sight-feed chamber. A junction-pipe JP leads down from 130

the flange SF⁴. On this junction-pipe are upper and lower flanges JP¹ JP². The flange JP¹ is bolted to the flange SF⁴. The junction-pipe is of bent form and when the upper flange JP¹ is horizontal the lower flange JP² is normal to an axis x—y inclined out of the axis a—b of the upper flange by an angle of forty-five degrees. There is a passage through the junction-pipe, the upper portion JP³ of this passage being at right angles to the flange JP¹, and the lower portion JP⁴ being at right angles to the flange JP².

Where these passages meet is a coned seating JP⁵ for a steam-valve SV constituted by the cone-pointed end of a spindle SV¹ screw-threaded into a boss JP⁶ of the junction-pipe which is provided with a stuffing-box JP⁷ of the usual or any convenient type. SV² is a hand-wheel on the spindle SV¹ for operating it. Threaded into the lower end of the junction-pipe JP is a tube SW constituting a virtual continuation of the passage JP⁴ and extending downwardly in the line of the axis x—y and out from the bottom of the instrument.

In the line of the inclined axis x—y is a tubular flanged bracket BR of H-section, with a central tube br cast in about the neutral axis of the section concentrically with the tube SW. This bracket has an upper flat end or flange BR¹ bolted to the flange JP² by four bolts BR³ and normal to said inclined axis x—y and has a lower flat end or flange BR² inclined by forty-five degrees out of a plane normal to said inclined axis x—y.

The four bolts BR³ are parallel to, and spaced apart at equal angular intervals around, the axis of the bracket BR. When the bolts are removed the bracket BR can be turned into four angular positions about the said axis in which the bolt-holes in the flanges BR¹ and JP² will coincide. In the position in which it is shown in Fig. 1 the bracket has its lower face BR² horizontal. By rotating the bracket through one hundred and eighty degrees out of that position the bolt-holes will be brought into a position of coincidence wherein the face BR² will be found in the vertical plane as shown in Fig. 2.

In Fig. 7 which is a view of part of Fig. 3 modified to show an alternative construction, the connection between the upper end of the bracket BR¹ and the lower flange JP²⁰ of the junction-pipe is made by eight parallel bolts distributed around the axis of the lower portion of the junction-pipe at equal angular intervals. With this construction the bracket BR can be rotated about the axis x—y, Fig. 1, into eight different angular positions in which the bolts will fix it, two of which positions will correspond to the position in which it is shown in Figs. 1

and 2 respectively, the others being intermediate angular positions in which the bottom face of the bracket BR will be askew, that is to say not in a horizontal plane as in Fig. 1, nor in a vertical plane as in Fig. 2, 70 but in an intermediate plane.

The instrument is intended to be secured upon cylindrical surfaces such as the exterior surfaces of steam-pipes, for example, which may be horizontally or vertically disposed, or inclined. To enable it to fit these surfaces closely, pads P* are provided. Each such pad has a flat surface, the edge of which is seen at P¹ in Figs. 1, 2, 4 and 6, and a cylindric surface P², the edge of which is seen in Figs. 4 and 6 and which is indicated also in Figs. 1 and 2. The cylindric surface is curved to suit the size of steam-pipe to which the device is to be fitted, and the flat surface abuts against the corresponding flat surface on the bracket BR. With any single instrument a number of these pads may be sent out if desired, to suit varying dimensions of steam-pipe, the curvature of the surface P² differing in the different 80 pads accordingly. Screws P³ pass through the lower portion of the bracket BR into the pad, to secure bracket and pad together. In the lower part of the bracket, holes H are provided above saddle-shaped projections 85 BS formed on the bottom of the bracket. 90

In Figs. 3 and 4 the instrument is shown secured to a pipe which is in section and is lettered X. From these views it will be seen that the holes H and saddle-pieces are to receive metal straps STR which pass through the holes and can be made to encircle the pipe and pass through a plate PL bearing against the opposite side of the pipe the straps being screw-threaded at their ends to 100 receive nuts n which when tightened pull the plate PL and pad P* toward one another so as to hold the instrument hard home upon the pad, and the latter upon the pipe, so that between the curved underface of the 110 pad P² and the pipe close contact will exist all around a hole in the pipe through which the tube SW will project into the steam-space.

The operation of the device is as follows:—The interior of the tube T is filled with graphite or other powdered material which is to be delivered into the pipe X or other steam-container to which the device has been secured in, e. g., the manner above 115 described. The inner tube T is adjusted up or down to afford the desired degree of opening through the notches N from the inner tube T into the funnel FL, and, the cap K being secured, the steam-valve SV 120 is opened. Steam rises up the pipe SW through the sight-feed chamber and up through the bore D² and also, more particularly, around the nozzle D⁷ and up the steam-conduits SC¹, SC², SC³ into the 125 130

jacket-space AS and on up the helical groove HG into the top end of the instrument. Radiation occurs facilitated by the wings W, and condensation of steam follows in 5 the jacket-space AS, these processes continuing so that water collects in the bottom of the space AS and passes downward out of it through the perforations P and passing on downward through the contents of the 10 inner tube over the top of the conical disk D and out through the notches N, carries with it some of the finely-divided material from the lower outer margin of the column. This material flows with the water down the 15 coned surface of the funnel, in between the wings D⁴ and down through the bore D², being delivered by the nozzle D⁷ down through the sight-feed chamber and passages SF³, JP³ and JP⁴, and thence, still 20 downward, along the lower side of the bore of the pipe SW to the delivery end of the latter. The rate of this flow will be dependent on the amount of condensation-water which collects in the jacket-space AS and 25 this can be controlled by suitably adjusting the steam-valve SV which determines the rate at which the steam-supply for condensation flows up from the pipe SW into the upper portion of the instrument.

30 While the lower outer edge of the column of material in the inner tube T is being thus eroded and carried away the material above gravitates downwardly to take its place and in this gravitation the central portion of the 35 conical disk D¹ acts as a central wedge in regard to the descending column tending to open its sides outwardly, away from its axis, preventing it from taking and clogging and directing it toward the notch outlets N.

40 The lower end of the inner tube T may be so formed and dimensioned that while it constitutes a valve with relation to the outer margin of the conical disk, it makes as to the exterior of the vertically-movable cylindric 45 valve, merely a sliding fluid-tight joint with the annular seating formed on the lower part of the jacket interior, without controlling openings P⁰ shown in dotted lines which can be situated at a slightly higher 50 level than the valve-controlled perforations P; for these latter they would be substitutes as far as the admission of water by them to the lower interior of the tube is concerned, though in such a case they would always be 55 open and would not (unlike the perforations P) be controlled by the parts F F¹ aforesaid.

What I claim as my invention and desire to secure by Letters Patent is:—

60 1. A lubricator for heavy lubricant comprising a steam jacket container, means for feeding steam to said jacket, feed openings for water of condensation from the jacket to the container, outlet openings from the 65 container for the water of condensation and

the lubricant, and means for adjusting the size of said openings, substantially as described.

2. A lubricator for heavy lubricant comprising a steam jacket container, means for securing said container to a steam pipe through which the lubricant is fed, means for feeding steam from the steam pipe to said jacket, feed openings for water of condensation from the jacket to the container, 70 outlet openings from the container for the water of condensation and the lubricant, connection between said outlet openings and the steam pipe to feed the water of condensation and the lubricant to the steam pipe, and means for regulating the amount of steam fed to said jacket, substantially as described.

3. A lubricator for heavy lubricant comprising a steam jacket container, means for securing said container to a steam pipe 85 through which the lubricant is fed, means for feeding steam from a steam pipe to said jacket, feed openings for water of condensation from the jacket to the container, outlet openings from the container for the water 90 of condensation and the lubricant, connection between said outlet openings and the steam pipe to feed the water of condensation and the lubricant to the steam pipe, and means for adjusting the size of said openings, substantially as described.

4. A lubricator for heavy lubricant comprising a steam jacket container, means for securing said container to a steam pipe through which the lubricant is fed, means 100 for feeding steam from a steam pipe to said jacket, feed openings for water of condensation from the jacket to the container, outlet openings from the container for the water of condensation and the lubricant, connection between said outlet openings and the steam pipe to feed the water of condensation and the lubricant to the steam pipe, means 105 for adjusting the size of said openings, and means for regulating the amount of steam fed to the jacket, substantially as described.

5. A lubricator for a heavy lubricant comprising a casing, a container therein, there being a steam jacket between the casing and the container, means for feeding steam to 115 said jacket, feed openings for water of condensation through the wall of the container for feeding water of condensation from the jacket to the container, outlet openings from the container for the water of condensation 120 and the lubricant, a plug in the lower end of said container and arranged to act as a valve for varying the size of the openings leading from the container, and means for adjusting the container for varying the size 125 of said openings, substantially as described.

6. A lubricator for a heavy lubricant comprising a casing, a container therein, means for closing the top of said casing, there being a steam jacket between the outer wall of 130

the container and the casing, openings through the wall of the container for the water of condensation to pass from the steam jacket into the container, means for supplying steam to the steam jacket, a valve member seated in the lower end of said container, there being openings from said container for the combined water of condensation and the lubricant, and means for adjusting the container relative to the valve member to vary the size of said openings, substantially as described.

7. A lubricator comprising a casing, a container for a lubricant therein, a seat in said casing adapted to be engaged by the periphery of the container to form a relatively tight joint, there being a steam space between the container and the wall of the casing above said seat, means for feeding steam to said steam space, a valve member seated in the lower end of the container, there being openings in the inner wall of the container through which the water of condensation and the lubricant are fed, and means for adjusting the container relative to said valve member to vary the size of said last mentioned openings, substantially as described.

8. A lubricator comprising a casing, a container for a lubricant therein, a seat in said casing adapted to be engaged by the periphery of the container to form a relatively tight joint, there being a steam space between the container and the wall of the casing above said seat, means for feeding steam to said steam space, a valve member seated in the lower end of the container, there being openings in the inner wall of the container through which the water of condensation and the lubricant are fed, means for adjusting the container relative to said valve member to vary the size of said last mentioned openings, and a removable cover for the casing, substantially as described.

9. A lubricator comprising a casing, a container for a lubricant mounted therein, a seat in said casing adapted to be engaged by the wall of the container, there being a steam space between the container and wall of the casing above said seat, there being openings through the wall of the container communicating with the steam space and the interior of the container, recesses in the inner face of the container below the upper edge of said seat and communicating with the interior of the container and a chamber within the casing below said seat, said container forming a joint with said seat, there being a second chamber below the last mentioned chamber, a passage in communication with the first and second chamber through which the lubricant passes, there also being a passage communicating with said second chamber and the steam space, and a valve controlled passage for admitting

steam to the second chamber and for permitting the lubricant and water of condensation to flow therethrough, substantially as described.

10. A lubricator comprising a casing, a container for a lubricant mounted therein, a seat in said casing adapted to be engaged by the wall of the container, there being a steam space between the container and wall of the casing above said seat, there being openings through the wall of the container communicating with the steam space and the interior of the container, recesses in the inner face of the container below the upper edge of said seat and communicating with the interior of the container and a chamber within the casing below said seat, said container forming a joint with said seat, there being a second chamber below the last mentioned chamber, a passage in communication with the first and second chamber through which the lubricant passes, there also being a passage communicating with said second chamber and the steam space, a combined closure for the container and the casing, and a valve controlled passage for admitting steam to the second chamber and for permitting the lubricant and water of condensation to flow therethrough, substantially as described.

11. A lubricator comprising a casing, a container for a lubricant mounted therein, a seat in said casing adapted to be engaged by the wall of the container, there being a steam space between the container and wall of the casing above said seat, there being openings through the wall of the container communicating with the steam space and the interior of the container, recesses in the inner face of the container below the upper edge of said seat and communicating with the interior of the container and a chamber within the casing below said seat, said container forming a joint with said seat, there being a second chamber below the last mentioned chamber, a passage in communication with the first and second chamber through which the lubricant passes, there also being a passage communicating with said second chamber and the steam space, a combined closure for the top of the casing and the container, means for adjusting the container longitudinally for varying the size of the openings from the container to the first chamber below the seat, and a valve controlled passage for admitting steam to the second chamber and for permitting the lubricant and water of condensation to flow therethrough, substantially as described.

12. A lubricator comprising a casing, a container for a lubricant threaded therein, a cover for said casing having conical walls, means for securing said cover in position, there being a recess for water of condensation in the upper end of the casing, a steam

space between the container and the jacket, there being a channel communicating with said steam space and a space for the water of condensation below the cover, means for feeding steam to said steam space there being a seat in the casing at the lower end of the steam space arranged to be engaged by the outer portion of the container, a valve member in the lower end of the casing, there being openings through the wall of the container above said seat for feeding water of condensation to the container, there also being openings leading from the inside of the container to the lower end of the casing through which the water of condensation and the lubricant pass, the container being arranged to be adjusted vertically with relation to the valve member to vary the size of said last mentioned openings, a connection with a steam pipe communicating with the steam feed for the steam space, a communication between said connection to the steam pipe and the lower end of the casing through which the water of condensation and the lubricant pass, and means for varying the amount of steam passing from the steam pipe to the steam space, substantially as described.

13. A lubricator comprising a casing, a container for the lubricant therein, there being a steam space within the casing surrounding the container, a seat in the lower end of said casing engaging the outer face of the container, a valve member in the lower end of said casing, there being openings from the steam space through the wall of the container for feeding water of condensation from said steam space to the container, openings through the lower end of the container around the edge of said valve, means for adjusting the container vertically to vary the size of said last mentioned openings, a closure for the upper end of the casing having conical walls, there being a channel in said casing below the apex of said walls for receiving the water of condensation which drips from the cover, there being a communication between said channel and the steam space, a chamber below said valve

member within the casing, a sight feed chamber below said last mentioned chamber, there being a passage communicating with the sight feed chamber and the chamber below the valve in the lower end of the casing, a steam connection between the sight feed chamber and the steam space between the casing and the container, and a connection from said sight feed chamber to a steam pipe through which the water of condensation and of the lubricant are fed and through which the steam is fed for heating the lubricator, and a valve in said connection for varying the opening to the steam pipe, substantially as described.

14. A lubricator comprising a casing having a yoke member pivotally connected thereto, a cover for the casing mounted in said yoke, and a screw for raising and lowering the cover with relation to the casing, substantially as described.

15. The combination of a lubricator and a plurality of attaching brackets having steam openings therethrough, each of said brackets having two securing faces at an angle to each other, and arranged to be secured in different positions to each other and with relation to the lubricator and the part to be lubricated, substantially as described.

16. A lubricator for heavy lubricant comprising a steam jacket container, means for feeding steam to said jacket, feed openings for water of condensation from the jacket to the container, and outlet openings from the container for the water of condensation and the lubricant, substantially as described.

17. The combination with a lubricator and a plurality of attaching brackets having steam openings therethrough, each of said brackets having two securing faces at an angle to each other and arranged to be secured in different positions to each other and with relation to the lubricator and the part to be lubricated, of a steam controlling valve in one of said brackets for controlling the flow of steam through said openings, substantially as described.

In testimony whereof I affix my signature.
LEONARD CHAPMAN.
